DIE FOR PRESSURE CASTING

Torbjorn C. Korsmo, Madison, Wis., assignor to
 Madison-Kipp Corporation, Madison, Wis., a
 corporation of Wisconsin

Application January 2, 1941, Serial No. 372,929

8 Claims. (Cl. 22—68)

This invention relates to dies for die casting machines, and particularly to apparatus for pulling the core from a die during the opening movement of the die parts.

The invention is an improvement on the structure of the Korsmo Patent No. 2,033,036, issued March 3, 1936 and extends the range of utility of the mechanism of that prior patent.

In the prior Korsmo patent the core pulling stress is delivered to the core-carrying slide through a carriage which is pivoted to the slide at a point intermediate its ends and has two pairs of rollers, one at each of its opposite ends, the rollers running, in pairs, on two sets of cam tracks which are supported by the combination bars forming a part of the die casting machine. The cams are so designed that as the movable part of the die retreats from its closed position one end of the carriage is shifted in a direction to pull the core, while the other one moves in a neutral path and serves as a fulcrum. Then the other end of the carriage is moved out while the first serves as a fulcrum, after which both ends of the carriage are guided to the extreme outward position in oblique parallel cam grooves. Thus the core-carrying slide was given two successive opening impacts which broke the core away from the casting, and the force of the impacts was multiplied by the lever effects of the carriage in its successive pivoting motions.

This mechanism has proved highly satisfactory in service. The present invention simplifies its construction considerably and extends its utility so that it is now peculiarly effective where heavy cores must be handled. In the Korsmo patented device the closing movement of the core was effected through the carriage and this required an adjustment of a part of the cam track. This adjustment, and the fact that the cam tracks were mounted on the machine rather than on the die, complicated the procedure in mounting the die in the machine. In the improved embodiment forming the subject of the present invention the cam tracks are so contrived that they can be mounted on the fixed portion of the die. Thus the mere mounting of the die in the machine assures correct location of the cam tracks. Further, the carriage mechanism and the cam tracks with which it coacts perform only the function of withdrawing the core. There is a separate cam which performs the function of returning the core to its operative position as the die closes. This second cam has only a light duty to perform, is never affected by the shocks delivered through the car-

riage during the core pulling function, and consequently can be manufactured with precision and requires no provision for adjustment. Thus the construction is simplified, installation of the dies is simplified, operation is improved, and the ability to handle heavy cores is enhanced.

There are other features of novelty and utility more or less related to the features above-mentioned and these will become apparent in connection with the detailed description of a preferred embodiment of the invention which will now be given with reference to the accompanying drawings.

In the drawings:

15 Fig. 1 is a plan view showing the positions assumed by the parts when the die is closed and the cores are in their operative positions.

20 Fig. 2 is a similar view showing the movable die part fully withdrawn and the cores withdrawn to their limiting outward positions.

25 Fig. 3 is a section on the line 3—3 of Fig. 1.

Fig. 4 is a side elevation of the carriage and tracks shown in the position of Fig. 1 and viewed in the direction of the arrow marked 4 on Fig. 1.

30 Fig. 5 is a fragmentary perspective view of the carriage, the upper end of the core carrier slide, and the tracks on which the carriage runs.

Fig. 6 is a perspective view of the core carrier slide and core.

35 Figs. 7-10, inclusive, are fragmentary views of the core actuating mechanism showing successive steps during the opening motion of the die. Fig. 7 shows the die closed. Fig. 8 shows the die starting to open and the carriage ready to deliver the opening impact to the core. Fig. 9 shows the position assumed after the core has been started. Fig. 10 shows the wide open position.

40 Referring first to Figs. 1 to 3, the general components of the die casting machine will be identified to indicate the environment in which the invention is used.

45 A portion of the main housing of the machine is indicated at 11, while 12 represents the so-called hot plate against which the fixed half of the die is mounted. This fixed half includes a main body 13 and two inserts, namely, the insert 14 which forms half of the die proper, and the insert 15 which forms half of the injection chamber in which the molten material, for example molten metal, is subjected to pressure to force it through the sprue 16 into the die proper.

50 Supported between the hot plate 12 and the housing 11 are two guide rods 17 which also serve as tension members between the hot plate and the main housing. Guided on these is a carriage 18

which is actuated by the ram 19. The ends of the carriage 18 are connected to the remote end of the ram by tie-rods which appear at 21. The carriage 18 has forward die supporting extensions 22 which are at the two sides of the carriage and which project forward, that is, to the left as viewed in Figs. 1 to 3, and are rigidly connected with the movable die half. This, as does the fixed die half, comprises three components, a main body 23, a die insert 24, and an insert 25 which forms the complementary half of the metal pressure chamber.

An ejecting mechanism is mounted in the interval between the two forward projections 22 and comprises two releasably connected plates 26 and 27. The plate 27 carries the ejector pins 28. These work through apertures in the movable die component and are normally retracted as shown in Fig. 3. They are urged to their retracted position by a plurality of coil compression springs one of which appears at 29. In order to operate the ejector pins 28 when the die is wide open, four adjustable studs 31 are threaded in the housing 11 and are so set that shortly before the die reaches fully open position the ends of the studs strike the plate 26 and by preventing the retreat of the plate 26 to the right while the movable die half is still retreating to the right, cause the pins 28 to protrude through the mold cavity in the die and strip the casting.

The springs 29 are not relied upon to cause retreat of the ejector pins 28 from the die cavity. Positive actuating means are provided and will now be described.

Mounted between the members 22 and against the forward face of the carriage 18 is a housing 32 in which is journaled a vertical shaft 33. This shaft carries an elongated pinion 34 which extends nearly its entire length. (See Fig. 1.) This pinion meshes with two racks 35 fixed on and projecting rearwardly from the plate 26. Thus any motion of the plate 26 relatively to the movable die portion entails rotation of the shaft 33.

Fixed to the upper end of the shaft 33 is a crank arm 36, which carries a roller 37. This roller engages the side of the track 38 fixed to the combination bar 39. The combination bar is an interchangeable element of the machine used to support any of various cam mechanisms which may be required for particular dies. The major portion of the active face of the track 38 engaged by the roller 37 is parallel with the motion of the carriage 18 but the end of the track is beveled as indicated at 41. The beveled portion 41 permits swinging motion of the crank 36 (see Fig. 3) after the adjustable pins 31 have engaged the plate 27. Thus, when the die is nearly fully open, the bar 39 permits protrusion of the ejector pins.

During initial motion in die closing direction the roller 37 travels up the inclined portion 41 and retracts the ejector pins positively, irrespective of the action of the spring 29. This retraction occurs in the first portion of the motion and the pins are held retracted in all positions between and including this and die closed position.

The plunger indicated at 42 is the plunger used to force molten metal into the die.

The parts so far described will be recognized as components of the die casting machine described and claimed in Korsmo Patent No. 2,033,036.

The cavity in the die inserts 14 and 24 requires the use therewith of two cores, a small

core 43 and a much larger core 44 which happen to be axially aligned. Both of these must be retracted as the die opens. The small core 43 is mounted on a slide 45 which is guided in the movable die part 23 to move in a direction transverse to the motion of the carriage 18. It is actuated by an inclined cam bar 46 which is fixed in the fixed die part 13 and which coacts with a slot 47 in the slide 45. A simple inclined cam bar is sufficient for the small core 43. Since no novelty is claimed for this particular arrangement, further description appears to be unnecessary.

The large core 44 whose operating mechanism includes the subject matter of the present invention is formed on the inner end of a slide 48 which is guided on the movable die member 23 and projects horizontally therefrom. The form of this slide 48 is clearly shown in Fig. 6. It carries a block 49 which seats against the two portions of the die when the latter is closed and which has on its outer face an inclined reaction or cam follower surface 51 which conforms in angle to and engages the inner faces of two oblique cam bars 52 and 53 which are sustained on the fixed die member 13.

The surface 51 coacting with the bars 52 and 53 is the means used to force the slide 48 inward to position the core as the two die parts close. As stated, it is wholly independent from the cam mechanism which draws the core 44 out of the casting during the opening movement of the die parts.

The outer surfaces of the bars 52 and 53 are straight but each is cut away, as indicated at 54 and 55, to form two similar curved dips or depressions which are in proximate faces of the two bars and extend approximately half the width of each bar. See Figs. 4 and 5.

A small carriage made up of two identical side bars 56 is pivoted on a pin 57 which passes through the bars and through the bearing 58 in the upper end of the slide 48. The bars 56 are tied together by a cross member 59 and by two roller-carrying shafts 61 and 62, the shaft 61 being longer than the shaft 62 and being provided with rollers 63 which extend the full width of the track members 52 and 53. The shorter cross shaft 62 carries two shorter rollers 64 which are also located closely adjacent the bars 56 but do not extend the full width of the bars 52 and 53. The construction is such that the rollers 63 are guided in a straight path from end to end of the bars 52 and 53, whereas the rollers 64 follow depressions or dips 54 and 55. The surface on which rollers 64 roll is clearly indicated in dotted lines on Fig. 1.

Referring now to Figs. 7 to 9 it will be observed that the parts are so proportioned that when the die parts are closed (Fig. 7) the rollers 64 are at the entrance to the depressions 54 and 55 and the rollers 63 do not even contact the bars 52, 53. The entrance contour of these depressions is approximately parallel with the path of travel of the carriage 18. Thus, as the die parts begin to open (see Fig. 8), the rollers 64 are permitted to move in a path parallel with the path of the carriage 18, whereas the rollers 63 are forced to move in a path oblique and outward relatively to the path of the carriage 18.

It will be observed that the pin 57 is closer to the shaft 62 than to the shaft 61, and consequently the carriage serves as a lever, developing a force ratio (which in the example illustrated is about 3 to 1) in an opening direction

upon the slide 48. The initial withdrawing impact is delivered to the core after the die parts have opened slightly as indicated in Fig. 8. In the position of Fig. 9 the force multiplying leverage action is still effective but will shortly diminish as the rollers 64 start to ride out of the depression. The positions assumed by the parts, in the full open position of the die parts, are clearly indicated in Fig. 10.

It will be observed therefore that during the initial opening of the die the core 44 is not shifted, but after partial opening, approximately in the position shown in Fig. 8, an opening impact is suddenly delivered to the core-carrying slide 48. The force multiplying action of the carriage continues for a period until the die has opened a little more than is indicated in Fig. 9. The final opening movement of the die occurs without the force multiplying effect on the carriage.

In the closing movement the beveled surface 51 acts as a closing cam so that the carriage has no closing effect. In fact, after the rollers 64 start to enter the depressions 54 and 55, there is clearance between the rollers on the carriage and the guide track. Thus the cam bars 52, 53 need not be adjustable. If the impact delivered through the carriage has any disturbing effect it will affect only the opening movement which need not be extremely precise. The closing movement of the core will not be affected and is positively controlled by the design of the member 49 and the inner faces of the bars 52 and 53.

What is claimed is:

1. The combination of a casting die comprising at least two parts; means for producing relative motion between said parts in a definite path to open and close the die; a core guided in one part of the die to move in a path suitable for withdrawal of the core from a casting formed in the die; cam means on the other part of the die and formed with two distinct cam tracks of different configuration; and two distinct cam followers associated with said core, one coacting with one cam track in the opening motion of the die to withdraw the core and the other coacting with the other cam track in the closing motion of the die parts to return and accurately position the core.

2. The combination of a casting die comprising at least two parts; means for producing relative motion between said parts in a definite path to open and close the die; a core guided in one part of the die to move in a path suited to the withdrawal of the core from a casting formed in the die; cam means on the other part of the die and comprising two distinct cams, namely, a core restoring cam and a core extracting cam, said extracting cam comprising two tracks of differing configuration as between themselves; a cam follower connected with the core and coacting with said restoring cam in the closing motion of the die parts to return and accurately position the core; and a cam follower carriage pivoted intermediate its ends to said core and having adjacent its opposite ends sets of rollers which respectively coact with said differing tracks in the opening motion of the die to withdraw the core.

3. The combination defined in claim 2 in which the extracting cam comprises two pairs of tracks of different gauges and the follower carriage has two pairs of rollers, the pairs being of different gauges, each pair of rollers corresponding and coacting with one of said tracks.

4. The combination defined in claim 2 in which the extracting cam comprises two pairs of tracks of different gauges and the follower carriage has two pairs of rollers, the pairs being of different gauges, each pair of rollers corresponding and coacting with one of said tracks, one of said tracks being straight and the other comprising a straight portion and an arcuate dip so located as to cause the carriage to function as a lever after the die has partly opened and then to deliver the initial opening impact to the core.

5. The combination of a casting die comprising at least two parts; means for producing relative motion between said parts in a definite path to open and close the die; a core guided in one part of the die to move in a path suited to the withdrawal of the core from a casting formed in the die; cam means on the other part of the die and comprising two distinct cams, namely, a straight line core restoring cam and a core extracting cam, said restoring and extracting cams being arranged obliquely to said path of relative movement of the die parts and said extracting cam comprising two tracks of differing configuration as between themselves; a beveled cam follower connected with the core and coacting with said restoring cam in the closing motion of the die parts to return and accurately position the core; and a cam follower carriage pivoted intermediate its ends to said core and having adjacent its opposite ends sets of rollers which respectively coact with said differing tracks in the opening motion of the die to withdraw the core.

6. The combination of a casting die comprising at least two parts, one of which is fixed; means for moving another part of the die in a definite path to open and close the die; a core guided in said moving part of the die to move in a path suitable for withdrawal of the core from a casting formed in the die; fixed cam means formed with two distinct cam tracks of different configuration arranged obliquely to said path of movement of the movable die part; and two distinct cam followers operatively connected with said core, one of said followers including lever-type force-multiplying means coacting with one cam track in the opening movement of the die part to withdraw the core, and the other follower including a beveled surface coacting with the other cam track in the closing movement of the die part to return and accurately position the core.

7. The combination of a casting die comprising at least two parts, one of which is fixed and the other of which is movable; means for moving the movable part of said die in a definite path to open and close the die; a core slide having a core part and guided in said movable die part to move in a path suited to the withdrawal of the core part from the casting formed in the die; fixed cam means comprising two distinct cams, namely, a core restoring cam and a core extracting cam, said restoring and extracting cams being disposed obliquely to said path of the movable die part and said extracting cam comprising two tracks of different configuration as between themselves; a cam follower located on the slide and including an inclined surface coacting with said restoring cam; and a cam follower carriage pivoted intermediate its ends to said core slide and having adjacent its opposite ends sets of rollers which respectively coact with said differing tracks.

8. The combination of a casting die comprising at least two parts; means for producing relative motion between said parts in a definite path to

open and close the die; a core slide having a core and guided in one part of the die to move in a path suited to the withdrawal of the core from a casting formed in the die; cam means comprising a pair of spaced cam bars rigidly supported on the other part of the die and projecting outwardly therefrom across the separation line of the die and obliquely to said relative path of motion of the die parts, the inner obliquely-disposed straight edges of the cam bars together forming a core restoring cam track, each cam bar having a depressed cam surface along its outer edge, said depressed surfaces together and the

obliquely-disposed straight outer edges of the cam bars together forming two core extracting cam tracks; beveled-surface cam follower means located on the slide and coacting with said restoring cam track; and a cam follower carriage pivoted intermediate its ends to said core slide and having sets of rollers at its ends coacting respectively with said extracting cam tracks, the core extracting cam track formed by said depressed surfaces being of such configuration as to cause the carriage to act as a lever to withdraw the core during opening of the die.

TORBJORN C. KORSMO.
